UNITED STATES PATENT OFFICE

CHARLES A. HOUSTON, OF SOMERVILLE, NEW JERSEY, ASSIGNOR OF ONE-THIRD TO WILLIAM B. MATHEWSON, OF SAME PLACE.

DRAFT-REGULATOR AND SPARK-ARRESTER.

SPECIFICATION forming part of Letters Patent No. 450,072, dated April 7, 1891.

Application filed July 8, 1890. Serial No. 358,118. (No model.)

To all whom it may concern:

Be it known that I, CHARLES A. HOUSTON, a citizen of the United States, residing in Somerville, in the county of Somerset and State of New Jersey, have invented certain new and useful Improvements in Draft-Generators and Spark-Arresters, of which the following is a specification.

This invention relates to tubular or multi-tubular steam-boilers, and particularly to that class of boilers wherein the tubes constitute the flues leading through the boiler from the furnace to the smoke-chamber.

The object of my invention is to provide improved means whereby a stronger and more uniform draft can be maintained, and to provide improved means for preventing the escape of sparks from the smoke-chamber.

To this end in carrying out my invention I construct a tubular shell within the smoke-chamber to inclose the discharge end of the flues, and extending thence to and surrounding the jet of exhaust-steam or other gaseous jet utilized to induce the draft, and extending thence upwardly and surrounding the smoke-stack by a closed connection, such shell having a contracted aperture in its forward portion for the escape of sparks. I also provide a tubular screen surrounding the jet and connecting with the smoke-stack, and I provide improved means for ejecting the sparks from the shell.

In the accompanying drawings, Figure 1 is a longitudinal vertical section of a locomotive-boiler and smoke-box and showing my invention applied thereto. Fig. 2 is a vertical transverse section thereof cut on the line 2 2 in Fig. 1, and showing the shell in front elevation. Fig. 3 is a vertical transverse section of a locomotive smoke-box cut on the line 3 3 in Fig. 1, and looking from the rear. Fig. 4 is a vertical transverse section similar to Fig. 1, but on a smaller scale, showing a simpler form of my invention; and Fig. 5 is a similar view of another form.

This invention relates more particularly to that class of draft-generators and spark-arresters which are shown and described in my application for patent filed October 9, 1889, Serial No. 326,420.

Referring to the drawings, let A represent the forward end of a locomotive-boiler; *a a*, the flues; B, the live-steam pipe; C, the smoke-box, and D the exhaust-steam nozzle. These parts are constructed in the usual manner. 55

Leading from the smoke-box C is the smoke-stack E, usually mounted directly over the nozzle D. According to my invention I extend the lower portion of the smoke-stack into the smoke-box C. This is preferably done by 60 inserting the tube E' into the lower end of the smoke-stack to form a downward continuation thereof. In the construction shown in Fig. 1 this tube continues downwardly and surrounds the nozzle D, being constructed at 65 its lower part in the form of a screen E², which is preferably tapered off at its lower end in the form of a cone and closely surrounds the upper portion of the nozzle D, on which it is seated. 70

Within the smoke-box C, I place a tubular shell F, arranged to inclose the discharge end of the flues *a a*, and extending thence forward and surrounding the jet end of the nozzle D, and extending thence upwardly and surrounding the lower portion of the stack by a closed connection therewith. The shell F is preferably constructed as a tube with an enlarged end for inclosing the flues, and extending forwardly and upwardly in a sweeping curve of rapidly-decreasing diameter toward its forward and upper end, where it incloses the lower end of the smoke-stack. The shell terminates in a raised forward portion *b* in front of the smoke-stack and near the top 85 of the smoke-box C. The shell F is preferably constructed of sheet metal, the form shown in the drawings being made up of four pieces—the rear or flue pieces *c c'* and the front halves *d* and *e*. These pieces are preferably 90 secured together by bolts passing through their flanges, as best seen in Fig. 2. The halves *d* and *e*, when removed from the piece *c*, permit access to the interior of the shell. The pieces *d* and *e* are constructed at their 95 upper sides with opposite recesses, which, when the pieces are in position, closely surround the lower part of the smoke-stack, this being, in Figs. 1, 2, and 3, the upper portion of the tube E'. This connection between 100

the pieces *d* and *e* is made by the tube E' being inserted into the tube F, and the pieces being forced together, the recesses in the pieces *d* and *e* being received in the flanges of the tube E'.

the shell F and the tube E' is constructed, as shown in Figs. 1 and 3, as a closed connection, and the upper portion of the shell is continued upwardly as it surrounds the tube, so 5 that the connection extends at an upward inclination from the back of the tube E' to the front thereof.

For permitting the escape from the shell F of any sparks coming through the flues a a 10 one or more apertures are provided in the shell. When one is used, it is preferably constructed in the upper portion b of the shell, and consists, preferably, of a contracted hole f in the forward side thereof, having outwardly-curved lips for facilitating the exit of 15 sparks and retarding any back-draft through the hole. If desired, the hole f may be omitted and an escape-aperture provided at some other point—such, for example, as the hole g 20 at the lower forward side of the shell, or both of these holes may be used at the same time. The holes f and g are located at points where any sparks entering the shell F will tend to pass. As the draft through the shell goes 25 upwardly through the screen E² and out through the smoke-stack E under the suction of the jet from the nozzle D, the sparks carried through the flues will be carried through the shell F in a sweeping curve with the 30 draft. Consequently centrifugal force will cause them to seek the outer and forward side of the shell up which they will travel. The heavier sparks will fall against the lower portion of the shell and pass out through 35 the hole g, while those which rise above that hole will be carried up and pass out of the hole f. Heavy sparks which strike the screen E² and then fall back are preferably ejected through the hole g by means of an auxiliary 40 jet directed toward the latter. This preferably consists of two pipes h h, having their ends extending into the respective compartments of the exhaust-steam nozzle D, and extending thence upwardly and laterally and 45 terminating in jet-nozzles at the respective sides of the exhaust-steam nozzle D, the pipes being shaped to catch a portion of the current of exhaust-steam passing through the nozzle D and discharging the portion of steam 50 so caught through their outer ends upwardly along the lower front wall of the shell F and toward the hole g. The jet of steam so discharged will carry out any sparks in its path.

Preferably an internal apron G is provided 55 within the shell F for isolating the hole g from the jet end of the exhaust-nozzle D, as best seen in Figs. 1 and 3. This apron preferably consists of a sheet-metal partition bolted to the section e of the shell F at i, and extending 60 thence downwardly from the upper side of the hole g and continuing in a direction parallel with the lower front wall of the shell F and terminating over the ends of the jet-pipes h h. The apron G closely surrounds the exhaust-steam nozzle D below the tubular screen 65 E², and serves as a partition which prevents the suction from the exhaust-steam jet from

drawing an inward current through the hole g, while it also serves to guide the auxiliary jet of steam outwardly through said hole.

The exhaust-pipe from the air-pump of the engine is shown at j entering the smoke-box C and carried through the latter to a core k in the nozzle D, which core terminates near the upper end of the nozzle in a small jet at 75 the forward side thereof. When the steam-pump is used, the exhaust therefrom passing from the pipe j and the core k jets out of the upper end of the latter within the screen E² and toward the smoke-stack, thereby supplementing the draft. The special steam-jet for creating a draft when the engine is not in operation is carried through the pipe l, entering the smoke-box C and discharging into the core m in the nozzle D, discharging through 80 the upper end of this core into the screen E², as best seen in Fig. 1.

In operation the exhaust-steam jet from the nozzle D, through the screen E² and pipe E' and out of the smoke-stack, causes a partial 90 vacuum within the shell F, which creates a draft from the flues a a, and the products of combustion are carried through the latter into the shell F, through the screen E², and out of the smoke-stack with the exhaust-steam. The draft is so closely confined within the shell F, by reason of the closed connection between the latter and the smoke-stack and the contracted spark-aperture, that the draft is practically isolated from the interior of the 95 smoke-box and confined directly to the flues a a, thereby securing the full force of the exhaust-suction independently of the condition inside the smoke-box. The sparks carried with the draft are guided onwardly in the 100 direction of their motion until they reach the spark-escape aperture, whereby their momentum is availed of to discharge them.

My invention provides an improved draft-generator and spark-arrester for boiler-furnaces, which is more effective than those heretofore used, which dispenses with the necessity of many complicated and draft-retarding screens and similar devices placed in the smoke-box for preventing the escape of sparks 115 therefrom. It permits the use of an exhaust-steam nozzle of larger diameter than heretofore, and in practice it has been found to effect a saving of twenty-five percentum in the fuel required in proportion to the power used. By isolating the draft from the smoke-box it 120 is only necessary for an exhaust-steam jet to maintain the desired rarefaction within the shell F, as no material part of the force of the exhaust is expended in overcoming leaks in the smoke-box or defective joints therein.

This invention can be variously modified without departing from its essential features, the construction heretofore described being the preferred form.

In Fig. 4 a simpler form embodying my invention is shown. In this construction the smoke-stack E extends into the shell F and terminates therein over the end of the ex-

haust-nozzle D. The latter is constructed as a simple nozzle discharging within the shell F. The shell F incloses the lower end of the smoke-stack by a closed connection, as well as 5 the upper end of the nozzle D, and terminates at its upper part b in the contracted aperture f.

Fig. 5 shows another form of my invention wherein it is used with especial reference to 10 increasing the draft. In this construction the shell F is entirely closed, surrounding the nozzle D and the lower end of the stack E by closed connections, whereby the draft is entirely confined within the shell. In this construction no provision is made for discharging 15 sparks from the shell F. The sparks which do not escape through the stack when this construction is used will be removed from time to time, as they accumulate in the 20 shell F, in any convenient manner.

What I claim is, in draft-generators and spark-arresters, the following-defined novel features and combinations, substantially as hereinbefore set forth, namely:

25 1. The combination, with a steam-boiler having flues through it, a smoke-chamber into which said flues discharge, a smoke-stack leading from the latter, a gaseous jet for creating a forced draft through the flues, and a 30 screen surrounding the jet and extending thence toward said smoke-stack, of a tubular shell within said chamber arranged to inclose the discharge end of the flues at one end, and extending thence to and surrounding the jet 35 below said screen, and extending thence upwardly and surrounding said stack above said screen, said shell constructed with a contracted aperture for the escape of sparks in its forward side, whereby the draft created 40 by the jet is confined within said shell, and the sparks entering said shell can escape through said aperture.

2. The combination, with a steam-boiler having flues through it, a smoke-chamber into 45 which said flues discharge, a smoke-stack leading from said chamber, a jet-nozzle discharging into said stack, and a tubular screen surrounding said jet-nozzle and leading to said stack, of a tubular shell inclosing the ends of 50 the flues at one end surrounding the jet-nozzle, and extending thence upwardly and surrounding the lower end of the smoke-stack by a closed connection therewith, and said shell constructed with a contracted aperture 55 in its upper and forward side for the escape of sparks, and with a contracted aperture in its lower and forward side, whereby the draft created by said jet-nozzle is confined within said shell and the sparks in the lower part of 60 the latter may escape through said lower aperture and those in the upper part thereof may escape through the upper aperture.

3. The combination, with a steam-boiler having flues through it, a smoke-chamber into 65 which said flues discharge, a smoke-stack leading from said chamber, a steam-nozzle discharging into said smoke-stack, and a tubular

screen surrounding said nozzle and extending thence toward said stack, of a tubular shell within said smoke-chamber inclosing the ends 70 of the flues at one end and surrounding the jet-nozzle, and extending thence upwardly and closely surrounding the lower end of said stack, said shell constructed with a contracted aperture in its forward side communicating 75 with said chamber for the escape of sparks, and a steam-jet discharging within said shell toward said aperture for expelling the sparks through it and into the smoke-chamber, whereby the draft created by the jet-nozzle is confined within said shell and the sparks in the latter are expelled therefrom through said aperture by said steam-jet.

4. The combination, with a boiler having flues through it, and a smoke chamber into 80 which said flues discharge, of a smoke-stack leading from said chamber, an exhaust-steam nozzle discharging into said stack and a screen surrounding said nozzle, of a tubular shell inclosing the ends of the flues at one end and 85 surrounding said nozzle, and extending thence upwardly toward said stack, said shell constructed with a contracted aperture for the escape of sparks in its forward side and having an internal apron above said aperture, 90 whereby sparks entering said shell may pass beneath said apron and escape through said aperture, and the draft created therein by said steam-nozzle is protected by said apron from said aperture. 95

5. The combination, with a boiler having flues through it, and a smoke-chamber into which said flues discharge, of a smoke-stack leading from said chamber; an exhaust-steam nozzle discharging into said stack, and a screen 105 surrounding said nozzle, of a tubular shell inclosing the ends of the flues at one end and surrounding said nozzle, and extending thence upwardly toward said stack, said shell constructed with a contracted aperture for 110 the escape of sparks in its forward side and having an internal apron, and an auxiliary steam-jet within said shell and discharging beneath said apron and toward said aperture, whereby sparks within said shell are dis- 115 charged by said jet through said aperture.

6. The boiler A, having flues through it, smoke-box C, into which said flues discharge, smoke-stack E, tubular extension E' thereof, exhaust-nozzle D and screen E², and the shell 120 F, inclosing the ends of the flues at one end and extending thence forward and surrounding the nozzle D and screen E², and surrounding the tubular extension E' by a closed connection therewith, said shell constructed with 125 contracted apertures f and g, and having internal apron G, in combination with the auxiliary jet-pipe h, constructed to take steam from the exhaust-nozzle D and discharge it in a jet beneath the apron G, all as and for 130 the purpose set forth.

7. The combination, with a steam-boiler having flues through it, a smoke-chamber into which said flues discharge, a smoke-stack lead-

- ing from said chamber, and a jet-nozzle dis-
charging into said stack, of a tubular shell
within said chamber inclosing the ends of the
flues at one end, surrounding the jet-nozzle
5 by a closed connection, and extending thence
upwardly and surrounding the lower end of
the smoke-stack by a closed connection there-
with, whereby the draft created by said jet-
nozzle is confined within said shell.
- 10 8. The combination, with a steam-boiler
having flues through it, a smoke-chamber into
which said flues discharge, a smoke-stack lead-
ing from said chamber, and a jet-nozzle dis-
charging into said stack, of a tubular shell
15 within said smoke-chamber inclosing the
ends of the flues at one end, surrounding the

jet-nozzle and extending thence upwardly and
surrounding the lower end of the smoke-stack
by a closed connection therewith, and said
shell constructed with a contracted aperture 20
in its forward side for the escape of sparks,
whereby the draft created by said jet-nozzle
is confined within said shell and the sparks in
the latter may escape through said aperture.

In witness whereof I have hereunto signed 25
my name in the presence of two subscribing
witnesses.

CHARLES A. HOUSTON.
